UNITED STATES PATENT OFFICE.

WILLIAM H. VOORHEES, OF WOODBRIDGE, NEW JERSEY.

SASH-LOCK FOR WINDOWS.

1,137,435.

Specification of Letters Patent. Patented Apr. 27, 1915.

Application filed January 13, 1914. Serial No. 511,930.

To all whom it may concern:

Be it known that I, WILLIAM H. VOORHEES, a citizen of the United States, residing at Woodbridge, in the county of Middlesex and State of New Jersey, have invented certain new and useful Improvements in Sash-Locks for Windows; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates to improvements in sash-locks for windows adapted to lock the window-sashes in closed or partially opened positions; the same comprising a lock-plate for attachment with one window-sash and a spring-actuated bolt or latch-mechanism for attachment with the other window-sash, the said bolt or latch mechanism being further provided with means for retracting the bolt or latch from its operative relation to said lock-plate, together with means for securing said retracting means against operation from the exterior of the window, or against accidental retracting movement.

The invention is clearly illustrated in the accompanying drawings, in which:

Figure 1 is a front or face view of the interior side of a window, having the usual upper and lower vertically movable window-sashes, the latter being equipped with my novel combined sash-lock and ventilating attachment, said window-sashes being shown in partially opened relation and locked by means of the sash-lock in such positions, against further movement. Fig. 2 is an enlarged detail face view of portions of said window-sashes and the sash-lock, illustrating the parts in their closed relation and locked by the sash-lock in such positions. Fig. 3 is a vertical section taken on line 3—3 in said Fig. 2, looking toward the sash-lock. Fig. 4 is a top or plan view of the novel bolt or latch-member of said sash-lock, its housing, and the manipulating and locking elements thereof; and Fig. 5 is a vertical section of the same, taken on line 5—5 in said Fig. 4. Fig. 6 is a detached face-view of the lock-plate of said novel sash-lock; and Fig. 7 is a vertical section of the same.

Similar characters of reference are em-

ployed in all of the hereinabove described views, to indicate corresponding parts.

Referring now to the several figures of the said drawings, the reference character 1 indicates any ordinary construction of window having the vertically movable upper window-sash 2 and lower window-sash 3. Connected with one of the vertical stiles 4 of the upper window-sash 2, by means of screws 5, or any other suitable fastening means, so as to be properly positioned or located thereon is a lock-plate 6. Said lock-plate is provided with bolt-receiving openings 7 and 8.

The reference-character 9 indicates a housing or casing, having laterally extending perforated ears or lugs 10, through which may pass fastening screws 11, or any other suitable fastening means, whereby said housing or casing may be properly positioned and secured upon the upper surface of the meeting rail 12 of the lower window-sash 3, and in proper alignment with said lock-plate 6. Slidably mounted in the housing or casing 9 is a bolt or latch-member 13, the nosing 14 of which normally projects through an opening 15 located at the inner end of the housing or casing. Connected with the interior end of said bolt or latch-member 13 is a perforated lug or ear 16.

The reference-character 17 indicates a retractor-arm which enters a vertically elongated slot 18 formed in the outer end of said housing or casing 9, the interior end of said retractor-arm 17 being provided with a perforated lug or ear 19 which registers with the lug or ear 16 of the bolt or latch-member 13, so that a pintle 20 may be passed through the said respective lugs or ears, and whereby the retractor-arm 17 is pivotally connected with the interior end of said bolt or latch-member. This pivotal connection of the retractor-arm 17 with the bolt or latch-member permits of a slight vertical oscillatory or swinging movement of the member 17 with relation to said bolt or latch-member 13 and the housing or casing 9, such movement being permitted by reason of the said vertically elongated opening or slot 18 through which the exterior end of said retractor-arm projects. The said exterior end of said retractor-arm 17 is provided with an annular shoulder 21 which serves to limit the inward movement of said arm and the said bolt or latch-member connected therewith. Connected with the said exterior end of the re-

tractor-arm 17 is a vertically and upwardly extending portion 22, formed at its upper end with a rearwardly extending member 23, from the free end of which projects a downwardly extending latch-nosing 24, and an upwardly extending finger-piece 25. Connected with the forward upper marginal edge of said housing or casing 9 is an upwardly projecting rib or holding lug 26, and said latch-nosing 24 is chamfered on its outer side as at 27, so that said latch-nosing may be pushed rearwardly over said rib or holding lug 26 and caused to engage the same, to thereby lock said retractor-arm 17 against any retracting or outward movement, and consequently of said bolt or latch-member 13. Mounted within the interior of said housing or casing 9, so as to press against said bolt or latch-member 13, where-by the same is projected from and maintained in its outwardly projected relation to said housing or casing, is a compression spring 28 which is preferably coiled around said retractor-arm 17, so that one end engages the front wall of the housing or casing, while the opposite end engages the interior end of the bolt or latch-member 13. When the window-sashes are closed, as shown in Figs. 2 and 3 of the drawings, the main bolt-receiving opening 7 of said lock-plate 6 is registered opposite the end of the bolt or latch-member 13 projecting from said housing or casing 9, so that the spring 28 causes the nosing 14 of said bolt or latch-member 13 to be projected into said main bolt-receiving opening 7 by reason of said spring's outward thrust upon said bolt or latch-member 13. As thus positioned, the several parts of the sash-lock co-operate to lock and maintain the two window-sashes 2 and 3 in their closed relations against opening until the bolt or latch-member 13 is retracted from said main bolt-receiving opening 7 of said lock-plate 6, and thus disengaged from the said lock-plate 6. When said bolt or latch-member moves into locking position by the action of the spring, the retractor-arm 17 is pulled inwardly until the latch-nosing 24 moves over the rib or holding lug 26, whereupon the nosing engages the back edge of said rib or lug and prevents the retraction of said retractor-arm 17 and the said bolt or latch-member 13, unless manipulated from the inside of the window. When it is desired to open or move either window-sash 2 or 3, or both, the finger-piece 25, or any portion of the vertical part 22 must be grasped and moved upwardly to

release the latch-nosing 24 from its engagement with the rib or holding lug 26, the vertical swinging movement of said retractor-arm 17, owing to its pivotal connection wjth said bolt or latch-member 13, rendering such a lifting manipulation possible. After the latch-nosing 24 has thus been released from engagement with the rib or holding-lug 26, the retractor-arm 17 may then be pulled outwardly thereby retracting the bolt or latch-member 13 against the tension of said spring 22, and removing said bolt or latch-member from its engagement with the lock-plate 6. When thus removed, it is possible to open either of the window-sashes to their full extent.

I claim:—

In a device of the kind described, a casing for attachment to one window-sash, a spring actuated bolt slidably mounted in said casing so as to be projected from one end of said casing, a nosing on the outer end of said bolt, a retractor-arm pivotally connected with the interior end of said bolt and capable of a vertical swinging movement relative to said bolt, the outer end of said casing having a vertically elongated opening through which the exterior end of said retractor-arm extends, a shoulder on the exterior end of said retractor-arm adapted to engage the outer end of said casing to limit the inward movement of said retractor-arm and the projection of the nosing of said bolt, means for locking said retractor-arm against its bolt retracting movement, comprising an upwardly extending vertical portion connected with the exterior end of said retractor-arm, a rearwardly extending portion parallel to said retractor-arm connected with the free end of said vertical portion, a depending latch-nosing at the free end of said rearwardly extending portion, a holding rib at the upper forward marginal edge of said casing with which said latch-nosing engages, said latch-nosing being released from such engagement by the upward vertical swinging movement of said retractor-arm and its vertical and rearwardly extending portions, and a lock-plate for attachment with the other window-sash with which the nosing of said bolt engages.

In testimony, that I claim the invention set forth above I have hereunto set my hand this 10th day of January, 1914.

WILLIAM H. VOORHEES.
